C. S. SINCLAIR

PROCESS FOR CREATING A LEATHER EFFECT

Filed Sept. 15, 1923

FIG. 1

FIG. 2.

FIG. 3.

Inventor
CHARLES S. SINCLAIR.

By *Walter Murray*

Attorney

UNITED STATES PATENT OFFICE.

CHARLES S. SINCLAIR, OF CINCINNATI, OHIO, ASSIGNOR TO THE R. F. JOHNSTON PAINT COMPANY, OF CINCINNATI, OHIO, A CORPORATION OF OHIO.

PROCESS FOR CREATING A LEATHER EFFECT.

Application filed September 15, 1923. Serial No. 662,811.

To all whom it may concern:

Be it known that I, CHARLES S. SINCLAIR, a citizen of the United States of America, and a resident of Cincinnati, in the county 5 of Hamilton and State of Ohio, have invented a new and useful Improvement in a Process for Creating a Leather Effect, of which the following is a specification.

An object of my invention is to provide a 10 process whereby various surface effects may be artificially and arbitrarily created.

Another object of my invention is to provide a process whereby said effects may be expeditiously and economically produced.

15 These and other objects are attained by the means described herein and disclosed in the accompanying drawings, in which:

Fig. 1 represents a surface, various portions of which have undergone various steps 20 of my process.

Fig. 2 is a transverse sectional view on line 2—2 of Fig. 1.

Fig. 3 is a transverse sectional view on line 3—3 of Fig. 1.

25 Although I am about to explain my process as shown for producing a leather effect, it will be readily apparent that same may be applied for accomplishing various other effects such as marble, etc.

30 A ground color 4 is first applied to a surface such as 5. A rubber stamp or the like is then used for applying a given design as shown at 6. The design 6 is applied over the ground color 4. A rubber sponge or the like may then be applied for stippling over 35 the design and ground color as shown at 7. If desired the stippling may be accomplished by applying ink or paint of a slightly different shade from that used for

effecting the configuration 6. After the figure 40 6 and stippling 7 have dried, a coat of varnish 8 is applied over the entire surface.

Automobiles treated as disclosed herein are given novel, new and attractive appear- 45 ances.

Any suitable colored material may be used for effecting a given design, for example ink, dye, paint, size or varnish may be used.

50 My process accomplishes a somewhat mottled effect and the mere fact that dirt may get into the coloring will have no appreciable effect. My process is especially adaptable to automobiles because the mottled 55 effect neutralizes to considerable extent the unsightliness caused by the dust and the dirt wherewith automobiles are covered after any short distance of travel.

What I claim is:

1. A process of surface decoration comprising the application of a ground color to a given surface, applying a design over the ground surface, and stippling over the ground surface after the application of a 65 design.

2. A process of surface decoration for producing leather effects comprising the application of a ground color to a given surface, applying a design over the ground surface, stippling over the ground surface after the application of a design, and varnishing over the ground color, the design and the stippling.

75 In testimony whereof, I have hereunto subscribed my name this 8th day of September, 1923.

CHARLES S. SINCLAIR.
